UNITED STATES PATENT OFFICE

EDWIN POPE, OF QUEBEC, QUEBEC, CANADA

TYPEWRITER

Application filed November 19, 1930. Serial No. 496,577.

My invention relates to improved, and preferably supplemental, means for actuating the keys, and keybars, of conventional typewriters, through the instrumentality of a separate set of finger keys bringing into play electrical apparatus to assist in the operation of typewriter keys and key bars.

Objects of my invention are to improve the method of operating a supplementary finger keyboard by the utilization of electrical means to assist and complete the key movements selected and initiated by the operator;

To employ for this purpose a single source of electrical energy operating a single key actuating means;

To place this single key actuating means under the common control of all the finger keys, so that the operation of any selected key will call into play the common electrical means;

To thereby dispense with a plurality or multiplicity of electrical operating means involved when separate keys call into play separate electrical operating units;

To simplify the supplementary operating apparatus so as to increase its efficiency and eliminate sources of complication and arrangement;

To reduce the cost of construction of the supplementary operating apparatus without impairing its efficiency;

And to accomplish other desirable results as will be hereinafter pointed out.

In the drawings Fig. 1 is a plan view of my apparatus, medial finger keys and their bars being omitted for clearness, some finger keys of a typewriter set being shown to make the operation of my apparatus more easy to understand; Fig. 2 is a side elevation, taken as looking to the left on Fig. 1; Fig. 3 is an elevation taken as looking to the right on Fig. 2, duplicate medial portions being broken away for clearness; Fig.

4 is a detail taken as on the line 4—4 of Fig. 1, looking to the left; Fig. 5 is a detail taken on the line 5—5 of Fig. 1 looking to the left.

Similar parts are designated by similar reference numerals in all the figures.

The operative parts of the apparatus are

assembled in a suitable frame 1, which is preferably provided with adjusting means, such as screws 2, 2, 3, 3, whereby the apparatus may be conveniently positioned to properly cooperate with the typewriter finger keys.

Two series of bars, 4, 4, 4, and 5, 5, 5, are pivoted, as on a rod 6, in the frame, preferably spaced by slots 7, 7, 7 in a plate 8 attached to the front of the frame 1. The bars 4, 4, 4 and 5, 5, 5 also register in slots 9, 9, 9 in another plate 10 attached to the front of the frame.

The bars 4, 4, 4, are provided with finger keys 11, 11, 11, which may be marked to correspond with the typewriter keys to be severally actuated through them. And these bars 4, 4, 4 are also provided with laterally projecting flanges or arms 12, 12, 12 which lie over the adjacent bars 5, 5, 5, so that the depression of a bar 4 carries down also a bar 5.

Each bar 5 is provided with a downwardly extended member shown as consisting of a rod 13 threaded through a block 14 on the bar 5, this threaded connection permitting accurate adjustment between the rods 13 and the typewriter keys 15, 15, 15, with which they engage in operation.

A space bar 16 is carried by arms 17, 17 pivoted like the bars 4, 4, 4, and 5, 5, 5, in the frame 1, and controlling, through an arm 18 a bar 19, provided with a block 14 and pin 13 like those on the bars 5, 5, 5, so that the space bar 20, of a typewriter may be operated through the space bar 16, in a way similar to the operation of the typewriter keys through the keys 11, 11, 11.

A bar 23 extending across beneath all the bars 4, 4, 4 and 19 is carried by arms 24, 24 pivoted as at 25, 26 to the frame, and is normally held to duty by a spring 27 attached to one of the arms 24 and fastened to the frame 1.

An arm 28 extends down from each bar 4 into close proximity to the bar 23, so that depression of any bar 4 will rock down the bar 23; and a similar arm 28 extends down from one bar 17.

Another bar 30 is carried by arms 31, 31

pivoted to arms 32, 32, which, in turn are pivoted, as at 33, 33, to the frame 1, and carry an armature 34, in the field of electromagnets 35, 35, which lie in a circuit including a source of electrical energy, as battery 36. The armature is normally retracted from the magnets by a spring 37.

Plates 38, 38 extend from the frame 1 beside the arms 31, 31, and are each provided with a cam slot 39, into which projects a pin 40 from an arm 31.

Each bar 5 carries an arm 43, having a projection 44 lying in proximity to bar 30, and adapted to engage and hold below it.

15 Bar 19 also carries an arm 43.

The bar 23 lies above and in close proximity to the arms 32, 32, so that when the bar 23 is depressed by a bar 17 or 4 it carries down also the arms 32, 32 and the bar 30 carried by them, this downward movement resulting in the pins 40, 40 being drawn down in the cam slots 39, 39, throwing the upper ends of the arms 31, 31 and the bar 30 over toward the arm 43 so that the bar 30 is above the projection 44 and will prevent the bar 5 from rising, until it is released.

One of the arms 24, for instance the one to the right in Fig. 1, is provided with a point, as 46, adapted to contact with a flat spring 47, secured to the frame 1, when the arm 24 is depressed, thus closing a circuit through the spring 47, line 48, battery 36, line 49, coils of magnets 35, 35, line 50, and arm 24, so as to energize the magnets 35, 35, which 35 will draw towards them the armature 34, depressing the free ends of arms 32, 32, pulling down the bar 30, and through it the bar 19 or 5, completing the stroke of the bar to actuate the typewriter key to perform its normal 40 function in the operation of the typewriter.

An adjusting screw 51, in an extension of frame 1, the end of which screw may register with insulation 52 on spring 47 permits the proper regulation of the gap between point 45 46 and spring 47.

The release of a finger key 11, by the operator, after a printing stroke, allows spring 27 to rock arms 24, 24 and bar 23 upward, breaking the contact at 46, 47, deenergizing 50 the electro magnets, raising keybar 4 to its normal position, and permitting spring 37 to raise arms 32, 32, arms 31, 31, and bar 30, so that keybar 5 may be returned to its normal position by the typewriter key, as 15.

55 The operation of the mechanism is as follows:

The supplementary key board having been properly adjusted in reference to the typewriter key board, the operator selects and 60 lightly presses a finger key, as 11, thus depressing a bar 4 and its companion bar 5, pressing down bar 23, and arms 24, 24, closing the electric circuit at contacts 46, 47 energizing the magnets 35, 35 to draw toward 65 them the armature 34, depressing the free

ends of the arms 32, 32, throwing the bar 30 in over projection 44 and pulling it and bar 5 down with a quick stroke, through pin 13, to drive the typewriter key 15 down smartly to print the selected character.

The release of key 11 by the operator allows the arms 24, 24 and bar 23 to be raised, as already described, breaking the circuit at contacts 46, 47, permitting the arms 32, 32 to rock up, withdraw bar 30 from control of the key bar 5, and let that keybar be returned to normal position by the recoil of the typewriter key 15.

70 The short range of movement of the bars 4, 4 permits their return to normal position with marked rapidity, thus correspondingly increasing the speed with which the apparatus may be operated.

75 It will be seen that in my improved apparatus I employ but a single electrically actuated unit, embracing one or more electromagnets influencing a single armature and located in a single circuit, and that I employ this single armature to complete the printing stroke of any selected character, the initial movement only being given by the operator's 80 touch and the printing blow being delivered by the armature quickly and forcefully and immediately followed by the automatic return of the various elements to their normal 85 positions.

90 It will be understood that the number of finger keys and their cooperating elements in my supplementary apparatus may be varied to correspond with the number of typewriter 95 key elements with which the particular typewriter to be operated through the supplementary apparatus is supplied, for the principles of operation of the supplementary apparatus are the same whether there be a 100 larger or smaller number of typewriter keys in any particular typewriter. To avoid crowding, I have not illustrated supplementary keys for operating the typewriter shift 105 keys. But it is to be understood that elements 4, 5 and 11 are provided to actuate the 110 shift keys. Also, a single finger key 11 may be substituted for the bar 16 if that is desired; as the connections of 16 are the equivalents of 4, 5.

115 Furthermore the principles of my invention may be embodied directly in the typewriter itself. For it will be obvious that the typewriter finger keys may be disconnected from the type bars and made to actuate auxiliary bars like 5, 5 which, in turn may be connected to and actuate the type bars.

120 It is also to be understood that the particular form of embodiment of my invention is to be regarded as a typical and not an exclusive form; for details of construction may be modified, as by the use of mechanical equivalents, without departing from the spirit of my invention and the scope of my 125 claims.

Having thus described my invention, what I claim and desire to secure by Letters Patent of the United States is:

1. In mechanism adapted to actuate the finger keys of a conventional typewriter, the combination of selective finger key bars disposed in a common plane, a plurality of impulse bars parallel to and in the same plane as the finger key bars, alternated therewith and each initially compressible by a finger key bar, a source of electrical power, electrically driven impulse means, and common means controlled by any of the finger key bars to initiate the action of the impulse bars.

2. In mechanism adapted to actuate the finger keys of a conventional typewriter, the combination of selective finger key bars disposed in a common plane, a plurality of impulse bars parallel to and in the same plane as the finger key bars, alternated therewith and each initially compressible by a finger key bar, a source of electrical power, electrically driven impulse means engageable with any of the impulse bars, and common means controlled by any of the finger key bars to initiate the action of the impulse bars, the finger key bars and the impulse bars swinging on a common pivot line.

30 3. In mechanism adapted to actuate the finger keys of a conventional typewriter, the combination of selective finger key bars disposed in a common plane and each provided with a lateral extension, a plurality of impulse bars parallel to and in the same plane as the finger key bars, alternated therewith and each initially compressible by the lateral extension of a finger key bar, a source of electrical power, electrically driven impulse means engageable with any of the impulse bars, and common means controlled by any of the finger key bars to initiate the action of the impulse bars.

45 4. In mechanism adapted to actuate the finger keys of a conventional typewriter, the combination of selective finger key bars disposed in a common plane, a plurality of impulse bars parallel to and in the same plane as the finger key bars, alternated therewith and each initially compressible by a finger key bar, a source of electrical power, electrically driven impulse means engageable with any of the impulse bars, and common means controlled by any of the finger key bars to initiate the action of the impulse bars, the impulse bars being provided with adjustable elements to engage the typewriter finger keys.

5. In mechanism adapted to actuate the finger keys of a conventional typewriter, the combination of selective finger key bars disposed in a common plane, a plurality of impulse bars parallel to and in the same plane as the finger key bars, alternated therewith and each provided with a depending arm

having a lateral extension, and being initially compressible by a finger key bar, a source of electrical power, electrically driven impulse means engageable with the extension of the depending arm of any of the impulse bars, a cam embodying element for governing the engaging movement of the impulse means, and common means controlled by any of the finger key bars to initiate the action of the impulse bars.

6. In mechanism adapted to actuate the finger keys of a conventional typewriter, the combination of selective finger key bars disposed in a common plane, a plurality of impulse bars parallel to and in the same plane as the finger key bars, alternated therewith and each initially compressible by a finger key bar, a source of electrical power, electrically driven impulse means engageable with any of the impulse bars, and common means controlled by any of the finger key bars to initiate the action of the impulse bars, the finger key bars being free to return to normal position independently of the impulse bars.

7. In mechanism adapted to actuate the finger keys of a conventional typewriter, the combination of selective finger key bars disposed in a common plane, a plurality of impulse bars parallel to and in the same plane as the finger key bars, alternated therewith and each initially compressible by a finger key bar, a source of electrical power, electrically driven impulse means engageable with any of the impulse bars, and common means controlled by any of the finger key bars to initiate the action of the impulse bars, the impulse bars being free to complete their impulse movements independently of the finger key bars. 90 95 100

8. In mechanism adapted to actuate the finger keys of a conventional typewriter, the combination of selective finger key bars disposed in a common plane, a plurality of impulse bars parallel to and in the same plane as the finger key bars, alternated therewith and each initially compressible by a finger key bar to close a switch in an electrical actuating circuit, a source of electrical power, electrically driven impulse means engageable with any of the impulse bars, and common means controlled by any of the finger key bars to initiate the action of the impulse bars.
